UNITED STATES PATENT OFFICE.

GUSTAV VOGT, OF LIMOGES, FRANCE.

DESIGN FOR A DISH-HANDLE.

SPECIFICATION forming part of Design No. 15,045, dated June 3, 1884.

Application filed April 11, 1884. Term of patent 7 years.

To all whom it may concern:

Be it known that I, GUSTAV VOGT, of Limoges, in the Republic of France, have invented 5 a new and original Design for Dish-Handles, of which the following is a full, clear, and exact description, reference being had to the accompanying drawings, making part of this specification, in which—

Figure 1 represents a side view of a tureen 10 with my handle, and Fig. 2 a detail side view of my design for a dish-handle.

Similar letters of reference indicate corresponding parts.

The design relates to handles for dishes of 15 all kinds; and it consists of a curved handle having volute-shaped ornamentation at the ends and exterior leaves at the ends of the handle.

A in the drawings represents the curved 20 main portion of the handle, which is provided with volute-shaped terminals *aa*, that form the connection with the cover B or body C of the dish. From the volute-shaped terminals *aa* extend at the outside of the handle ornamental

leaves *bb*. The middle portion of the handle 25 is left smooth.

Having thus described my design, I claim as new and desire to secure by Letters Patent—

1. The design for a dish-handle, composed of a curved main portion having volute-shaped 30 terminals and exterior ornamental leaves at the terminals, substantially as shown and described.

2. The design for a dish-handle, composed of a curved main portion having volute-shaped 35 terminals and exterior ornamental leaves extending from the terminals toward the smooth middle portion of the handle, substantially as shown and described.

In testimony that I claim the foregoing as 40 my invention, I have signed it this 20th day of February, 1884.

GUSTAV VOGT.
